SPLIT SUTURE ATTACHMENT FOR FULL-FASHIONED KNITTING MACHINES

Frederick C. Good, Philadelphia, Pa.

Application September 2, 1938, Serial No. 228,101

21 Claims. (Cl. 66—128)

The present invention relates to split suture mechanism for full-fashioned hosiery knitting machines, and primarily aims to provide an attachment whereby a split knitted fabric may be produced on hosiery knitting machines provided with the so-called alternating "three carrier" attachment.

As known in the art, the main characteristic of split knitted fabric resides in the formation of a plurality of separate and distinct fabric sections joined together at the wales in the process of knitting, the yarn of one section forming no part of the other sections except at the juncture between the respective sections. These sections of fabric may be of equal thickness and different colors or quality; or they may be of different thickness and different colors; or of different thickness and the same color in either the same or a different quality of yarn.

In the manufacture of full-fashioned hosiery, split knitting is usually employed in the construction of the foot portion when it is desired to produce heel and sole areas having an increased wearing quality or a marked contrast with the adjoining portions of the stocking. For these purposes, the foot portion is formed of a central or instep fabric section knitted from relatively thin uniformly colored body yarn, and flanked on either side by the heel and sole fabric sections knitted from yarns of a heavier weight than, or of a color contrasting with, that of the body yarn.

With so-called "three-carrier" work, considerable difficulties have heretofore been encountered in producing a proper suture between the adjoining instep and heel and sole fabric sections, primarily due to the provision of the plurality of body yarn carriers alternately operated to lay their respective body yarns in repeated sequence throughout the sheer instep fabric section of the stocking foot portion.

The present invention, therefore, has for one of its main objects the provision of an improved attachment devised to control the body yarn carriers in their respective movements for laying their yarns to knit the instep fabric section and effect their arrest at the proper time in relation to the movements of the carriers intended to lay their yarns for the knitting of the heel and sole fabric sections, thus assuring the accuratelapping of the adjacent portions of the yarns over two or more needles for the formation of proper sutures.

Another important object of the invention resides in the provision of an attachment which may be readily mounted upon hosiery full-

fashioned knitting machines now in common use, without necessitating any material changes in the construction or operation thereof, said attachment being adapted for intimate association and cooperation with the various portions of such commonly used machines so that the function of the attachment is made to coact automatically with the working of the knitting machine.

The invention also contemplates the provision of an attachment of the type mentioned controlled through the pattern chain, Couller motions, and slur bar of the knitting machine, whereby the operation of the attachment is made dependent upon the function of said machine, thereby synchronizing the respective actions of the related mechanisms for accomplishing, to the best advantage, the formation of two or more needle lapped split sutures on hosiery knitting machines equipped with an alternating "three-carrier" attachment.

Still another important object of the invention contemplates the provision of a split suture fabric attachment having means capable of arresting any one of the plurality of body yarn carriers selectively controlled by the "three-carrier" mechanism and releasing but positively engaging the selected carrier when coming to the end of its traversing yarn laying stroke so that rebound is prevented, and accurate formation of overlapping suture loops accordingly assured, said attachment moreover including mechanisms operating through the pattern chain mechanism of the knitting machine to effect the automatic control of the carrier arresting and engaging means for its forward or reverse movements, thereby making it possible to control the laying of the yarns so that the split sutures may selectively be made to extend either inwardly or outwardly of the split fabric for the purpose of imparting to the stocking heel and sole any suitable or desired style or pattern.

It is also a distinguishing feature of the present invention to provide a split suture fabric attachment having a pair of body yarn carrier rod controlling devices, one of said devices being adapted to control the carrier rods from the right side and the other of said devices being adapted to control the carrier rods from the left side of the knitting machine, and means associated with both devices to operate the same alternately whereby to eliminate the formation of extra long loops ordinarily apparent in split suture fabrics produced with attachments heretofore commonly in use.

Moreover, the invention is characterized by the

fact that the use of the attachment embodying the present invention is not limited to the formation of split suture fabrics, but may also be utilized advantageously in making so-called "Pointex" or high splice heels in conjunction with "three-carrier" work.

Other important objects and advantages of the invention will be in part obvious and in part pointed out hereinafter.

In order that the invention and its mode of operation may be readily understood by those skilled in the art, I have, in the accompanying drawings and in the detailed description based thereupon, set out a possible embodiment of the invention.

In these drawings:

Figure 1 is a face elevation of a stocking blank having its foot portion constructed in accordance with the invention.

Figure 2 illustrates, on a reduced scale, the completed stocking as made from the blank shown in Figure 1.

Figure 3 is a diagrammatic representation of the suture seam construction.

Figure 4 is an end elevation of the attachment as applied to the full-fashioned knitting machine.

Figure 5 is a rear elevation of the same.

Figure 6 is an enlarged detail in top plan of the actuating means of the carrier rod controlling mechanism.

Figure 7 is a rear elevation of the same.

Figures 8 to 11 inclusive are diagrammatic representations illustrating the sequence of operations of slur bar cams on the carrier rod control actuating mechanism.

Figure 12 is an enlarged section taken on line 12-12 of Figure 5.

Figure 13 is a detail in face elevation of a portion of the mechanism shown in Figure 12 with certain parts in section.

Figure 14 is a detail in side elevation illustrating the assembly of the actuating elements of the mechanism shown in Figures 12 and 13.

Figure 15 is a detail in face elevation illustrating certain elements shown in Figure 14 in operative position.

Figure 16 is a view similar to Figure 15 illustrating certain other elements shown in Figure 14 in operative position.

Figure 17 is a detail in face elevation of still other elements shown in Figure 14.

Figure 18 is an enlarged detail illustrating a portion of the pattern chain mechanism.

With more particular reference to the drawings, wherein like characters of reference will designate corresponding parts throughout, there are shown but those parts of a full-fashioned hosiery knitting machine which are essential to the clear understanding of the invention, the basic construction and operation of the knitting machine itself being that of the usual standard machine well known in the art.

Referring particularly to Figure 1, there is diagrammatically illustrated a full-fashioned stocking blank comprising the leg portion 1, and the foot portion 2 having the instep fabric portion 3, heel fabric portion 4, sole fabric portion 5, and toe fabric portion 6.

In accordance with the invention, the sheer leg and instep fabric portions 1 and 3 respectively are of the three-carrier "ringless" construction, that is, they are knitted from body yarns alternately fed from three cones so that no two consecutive courses of loops are knitted from the same cone of yarn; and the high heel and sole

fabric portions 4 and 5 are knitted from yarns different from the body yarns so that the foot portion 2 actually consists of three distinct fabric sections, that is, an intermediate fabric section 5 and two side fabric sections, the inner selvedge 7 of each side fabric section having an overlapping interlooping connection with the adjacent selvedge 8 of the intermediate fabric to form, what is well known in the art as, a split seam suture 9.

As hereinbefore stated, this invention is directed to an improved attachment capable of effectively controlling the body yarn carriers to lay the respective yarns for the attainment of a proper split suture in a stocking fabric of the construction above stated. In the drawings illustrating the improved attachment and its association and cooperation with a full-fashioned knitting machine, the reference character 10 designates the usual machine frame having the back beam 12, the center bed 14, and the supporting brackets 16. Of course, the machine includes the main cam shaft 18 through which the various motions of the knitting machine receive their movements.

Associated, in the usual way, with the main cam shaft 18 is the Coulier motion (not shown) devised to impart a reciprocating movement to the slur bar 22 and to the ordinary friction rod 24 arranged for longitudinal sliding movement in the supporting brackets 16 and adapted to carry the well-known alternating "three-carrier" attachment for the selective operation of the carrier rods R1, R2, and R3 mounted for reciprocation in the carrier rod brackets 26 over the knitting sections (not shown) conveniently mounted about the center bed 14. As well understood by those skilled in the art, the carrier rods R1, R2, and R3 are each provided with a stop, as indicated at S1, S2, and S3 respectively. Also operatively associated, in its customary manner, with the main cam shaft of the knitting machine is the pattern chain mechanism, parts of which have been shown in Figure 18, to be referred to more specifically hereinafter.

Suitably fixed upon the rear portion of the machine frame 10, as indicated at 28, is a pair of relatively spaced paralleling upright supporting arms 30 having their intermediate portions formed with a bearing 32 rotatably supporting a control shaft 34. For the sake of clarity in the drawings, there has been shown but one of such arms, it being understood that the other arm is identical to the one herein illustrated. Keyed, or otherwise secured, upon the shaft 34 is a lever 36 having its free end connected to one extremity of a rod 38, the other extremity of which is connected to a hinged bracket 39 mounted upon the rear beam 12 as indicated at 39' and carrying a roller 40 disposed for riding engagement with a cam block 42 slidably mounted on a carriage 43 arranged for longitudinal reciprocating movement in a casting 44 secured to the back beam 12 of the machine frame 10.

Positive contact of the roller 40 with the cam block 42 is assured by the action of a spring 45 having one end connected to the supporting arm 30 and its other end connected to the lever 36. The cam block 42 is provided with three surfaces a, b, and c, respectively adapted to cause the roller 40 to assume three different levels, thereby moving the lever 36 from a neutral position (the position A as shown by the full line in Figure 12 of the drawings) to either a lower position (as shown by the dotted line at B) or to an elevated position (as indicated by the dotted

line at C). The cam block 42 is held in its various positions by means of a dog 46 pivoted as at 48 to the fixed casting 44 and having three stepped latch portions a', b', and c' respectively disposed to engage the cam block 42 in the manner to be hereinafter explained.

Proper engagement between the cam block 42 and dog 46 is assured by means of a spring 50 normally urging the latching portions of said dog for positive engagement with the cam block. Sliding movement in the direction indicated by the arrow D is imparted to the cam block to bring the same in engagement with either latching portion b' or c' by means of a weight 52 attached to one end of a cable 54 having its other end connected to the cam block, as indicated at 55, and riding over a pulley 56 rotatably supported on the fixed casting 44. The cam block may be brought back from its engagement with the latching portion c' or b' to its engagement with the latch portion a' by means of a pull-back dog 58 pivoted, as at 60, to the carriage 43 for reciprocating movement therewith, and having a hook end 62 adapted to engage said cam block and carry the same along with the carriage for its reciprocating motion in the direction indicated by the arrow D'.

Reciprocating motion is imparted to the carriage 43 by means of a cable 64 having one of its ends secured to said carriage, as shown at 65, and the other of its ends attached to the usual long rocker arm of the well known Coulier motion of the knitting machine. The cable 64 may be kept taut and the carriage 43 maintained in proper relationship with its associated elements hereinbefore described by means of a pulling weight 66 attached to one end of a cable 68, having its other end suitably connected to the carriage 43, as indicated at 69, and riding over a pulley 70 arranged upon the casting 44.

In order to effect the disengagement of the holding dog 46 from the cam block 42 so that the latter may move from one position to another, said dog is preferably provided with a laterally projecting ear 71 with which a pin 72 carried by an adjacent portion of the pull-back dog 58 is adapted to contact. The casting 44 is also preferably provided with a pusher 74 traversing said casting so that one of its ends contacts said pull-back dog while the other of its ends protrudes below said casting for engagement with one branch of a bell crank lever 76 pivoted, as indicated at 78, to the under side of said casting, the other branch of the bell crank lever being connected to a cable 80 leading to a second bell crank lever 82 (Figure 18) operatively associated with the pattern chain 84 carrying sets of low buttons 86 and high buttons 88.

From the description of the mechanism so far described, and assuming that the relative parts are in the neutral position, it will be understood that during the working of the knitting machine, the carriage 43 together with the pull-back dog 58 constantly reciprocate since they follow the rocking motion of the long rocker arm by reason of the cable connection 64 and pulling weight 66. However, because of the engagement of the latching portion a' of the holding dog 46 with the cam block 42, the latter is held in such a position that the roller 40 remains in contact with the surface a of said cam block and, accordingly, maintains the control shaft 34 and lever 36 in the neutral position A. This neutral position is maintained as long as no button, through the function of the pattern chain 84, is brought into

engagement with the associated bell crank lever 82. When a low button 86 comes in contact with said bell crank lever 82, said lever is moved to exert a pull on the cable 80 and on the bell crank lever 76 thereby forcing the pusher 74 upwardly and, accordingly, lifting the pull-back dog 58 and holding dog 46 high enough to allow the cam block to clear the latching portion a' and slide to the point where it comes in contact with the latching portion b'. In this position of the cam block, the surface b thereof is brought in alignment with the roller 40, therefore causing the lever 36 and control shaft 34 to assume the position B.

When a high button 88 comes in contact with the bell crank lever 82, the same action as above described takes place, except that the lifting of the pull-back and holding dogs is sufficient to permit the cam block to pass beyond the latching portion b' and slide to that point bringing the block in engagement with the latching portion c'. In this latter position, the surface c of the cam block is caused to become aligned with the roller 40 and, therefore, raises the rod 38 to place the lever 36 and control shaft 34 in position C.

The purpose of the mechanism so far disclosed is for the automatic actuation of the body yarn carrier rod controlling mechanism which will now be described.

Adapted to be carried by the supporting arms 30 are the carrier control devices, designated in their entirety for convenience herein by the reference character 90 and 90', one of said devices 35 90 being constructed to control the body yarn carrier rods R1, R2, and R3 at the right hand of the knitting machine, and the other of said devices 90' being constructed to control said carrier rods from the left hand of the machine. Since both devices are identical in construction 40 and operation, only one has been shown completely in the drawings, and it is to be understood that the following description of the device shown likewise applies to the device omitted.

Rigidly mounted, as at 91, upon the upper extremity of each supporting arm 30 is a housing 92 enclosing a rotatable sleeve 94 slightly projecting out of one end of the housing and having its inner peripheral surface formed with a screw-thread 96 for cooperation with a screw-threaded spindle 98 received within the sleeve and provided with a shank portion 100 extending beyond the inner end of said sleeve and out of the other end of the housing 92. The spindle 98 is adapted 50 to be rotated by means of a pawl and ratchet mechanism 102 comprising a pair of relatively spaced toothed wheels 104 and 106 respectively mounted upon the extended end of said spindle and suitably fixed thereto. The ratchet teeth 55 of the wheel 104 are positioned to extend in a direction opposite to the ratchet teeth of the wheel 106 so that the spindle may be moved either in a clockwise or an anti-clockwise direction through a selective action of a double pawl 108.

As shown, the double pawl 108 consists of a pair of diametrically opposed fingers 110 and 112, one finger for each ratchet wheel, said fingers being pivoted together in tong-like fashion with their free ends normally urged to engage their respective ratchet wheels by means of an interconnecting coil spring 114. Operative motion is imparted to the pawl 108 by means of a lever 116 pivotally connected thereto preferably at the 60 pivotal point of the fingers 110 and 112, as shown

at 118, and rockingly mounted on the control shaft 34.

The free extremity 120 of the lever 116 is disposed in the path of travel of a cam 122 conveniently fixed to the slur bar 22 so that during the reciprocating movement of said slur bar, the cam 22 engages the lever end 120, thereby displacing the lever 116 to actuate the pawl 108 in the direction of arrow H for the operation of the ratchet. Of course, while one of the pawl fingers 110 or 112 is in engagement with its corresponding ratchet wheel, to actuate the same, the remaining finger is held out of engagement with its associated ratchet wheel. For that purpose, there is provided a disc 124 freely mounted upon the extended shank 100 of the spindle 98 between the spaced ratchet wheels 104 and 106.

A segment 126 of the disc 124 is formed to extend even with the teeth of said ratchet wheels to blank out the same for the purpose to be presently stated. The disc 124 is connected by means of a link 128 to a lever 130 keyed, or otherwise suitably fixed, to the control shaft 34 so that, upon movement of the latter, through actuation of the pattern chain mechanism already described, said disc is brought into three distinct positions, that is, the positions shown at A', B', and C' in Figure 12, and individually represented in Figures 14, 15, and 16, respectively.

When in position A', the disc blanks out the teeth of both ratchet wheels 104 and 106 adjacent the pawl fingers 110 and 112. In this manner, and as will more clearly appear from Figure 12, the fingers are lifted out of engagement with the ratchet wheels, accordingly rendering the ratchet mechanism inoperative.

Upon movement of the disc to the position C', that is, the position fully represented in Figure 15, the segment 126 of said disc, while blanking out the teeth of the ratchet wheel 106, will uncover the teeth of the ratchet wheel 104, thus permitting the pawl finger 110 to engage the latter, turning the ratchet mechanism clockwise, accordingly rotating the spindle 98 and causing the sleeve 94 to move outwardly of the housing 92.

When the segment 126 is moved to the position B', that is, the position fully illustrated in Figure 16, then the segment 126 of the disc 124 blanks out the teeth of the ratchet wheel 104 while uncovering the teeth of the ratchet wheel 106. In this position, the pawl finger 110 is thrown out of engagement with the teeth of the ratchet wheel 104 and the pawl finger 112 allowed to fall into engagement with the teeth of the ratchet wheel 106 so that, upon actuation of the pawl, the ratchet is caused to move in an anti-clockwise direction, thereby rotating the spindle 98 and consequently moving the sleeve 94 inwardly of the housing 92.

In order to prevent accidental movement of the ratchet mechanism, there is provided a spring pressed plunger 132 disposed for engagement with a notched disc 134 rigidly mounted upon the shank 100 of the spindle 98.

Rigid with that end of the sleeve portion projecting out of the bearing 92 is a stop plate 140 adapted, when in operative position, to lay in the path of travel of the carrier stops S1, S2, and S3 respectively arranged upon the carrier rods R1, R2, and R3. Because of this arrangement, it will be understood that the plate 140 will move with the sleeve 94 during its motion in and out of the housing 92 accordingly causing the arrest of the carrier rods at different points in the course of their traversing stroke.

Since my improved mechanism is particularly intended for use in connection with three-carrier attachments, means are provided to lock the carrier rods when arrested in their traversing stroke and during the yarn laying movement of another carrier rod. As illustrated in the drawings, such means comprise a resilient latch 142 supported upon the stop plate 140, as indicated at 144, the latch being disposed to engage the carrier rod stop and retain the same in snug engagement with the stop plate 140.

When my improved mechanism is not to be used, as, for instance, during the knitting of the upper portion of the leg blank, said mechanism may be thrown out of operative position by manually rotating the sleeve to bring the stop plate 140 and its associated element out of the path of travel of the carrier stops, thereby allowing the carrier rods to travel their entire stroke.

In order to prevent accidental rotating movements of the rotatable sleeve 94, the same is provided with a pair of slots 146 and 148 respectively cut at diametrically opposed points upon the outer peripheral surface of said sleeve to extend longitudinally throughout the length thereof. Said slots are disposed to engage a spring pressed pin 150 adapted to retain the sleeve in either of its adjusted positions without hindrance to the longitudinal movement thereof through actuation of the pawl and ratchet mechanism, in the manner hereinbefore stated.

In manufacturing stockings upon a knitting machine equipped with my improved attachment, the stocking blanks, such as that shown in Figure 1, are started at the welt and knitted down to the point P in the usual well known manner, that is, the body yarn or main carrier rods R1, R2, and R3 are selected through operation of the three-carrier tackle of the machine and alternately actuated to lay their respective yarns for the formation of the leg fabric portion I. During the knitting of said leg portion down to the point P, the split suture attachment embodying the present invention is placed and held in inoperative position in the manner hereinbefore stated so that the main carrier rods are free to reciprocate the full length of their stroke.

Upon reaching the point P where the split fabric is to begin, the machine is stopped and the split suture attachment positioned for operation by placing the stop block 140 of each of the carrier control devices 90 and 90' in the path of the carrier stops S1, S2, and S3, the main carriers being adjusted so that said stops are disposed between the stop blocks whereby the reciprocating movement of the main carrier rods is limited to lay their yarns over a certain number of intermediate knitting needles for the formation of the intermediate section of the split fabric portion. At the same time, additional carriers, threaded with yarn different from the body yarn, are brought into play and adjusted for operation over the end needles to knit the side fabric sections of said split fabric portion, it being understood that the operation and control of said additional carrier rods may be performed through the ordinary splicing or like mechanism usually present on full-fashioned knitting machines.

With the knitting machine adjusted in the manner stated, the knitting is carried on and, through the function of the various parts, the split fabric is produced. In practice, it is preferable that the control of the different carrier rods be such that the different yarns in each

course overlay the distance of two needles at the respective selvedges 7 and 8 of the intermediate portion and adjacent side portions of the split fabric, although it is to be understood that the yarns may be caused to overlap over a greater number of needles by a mere adjustment of the carrier rod controlling devices, such adjustment being well known to those skilled in the art.

As hereinbefore stated, my improved device is capable of producing a split fabric of any desirable shape or pattern. This is accomplished by a selective planned arrangement of the low buttons 86 and high buttons 88 on the pattern chain 84, respectively adapted to cause the two controlling devices 90 and 90' to move so that their respective stop blocks 140 are displaced towards and away from each other, that is, inwardly and outwardly of the fabric, in the manner hereinbefore stated, thereby shortening or lengthening the stroke of the carrier rods. Thus, while the bell crank lever 82 rides over a portion of the pattern chain 84 devoid of buttons, the control devices remain in inoperative position so that the split suture 9 assumes a straight line formation extending wale-wise of the fabric. However, when the bell crank lever is displaced by the low buttons 86 to set the control devices 90 and 90' in motion towards each other, then the split suture assumes a broken line formation stepping inwardly of the fabric, as indicated at 152 and when the bell crank lever 82 is displaced by the high buttons 88 to set controlling devices in motion away from each other, then the split suture assumes a broken line formation stepping outwardly of the fabric, as indicated at 154.

Preferably, the distance travelled by the controlling devices in their in and out motions is equal to the distance of two needles and, for that purpose, the distance between the teeth of the ratchet wheels 104 and 106 is equal to the distance of two needles but, obviously, the travelling distance of said control devices may be varied by utilizing ratchet wheels having their teeth spaced to correspond to a lesser or a greater number of needles and readjusting the associated parts accordingly.

In accordance with the present invention, the two control devices 90 and 90' are adapted to be actuated alternatively, that is, the control device 90 at the right hand of the knitting machine is adapted to operate with the laying of a yarn from the right to the left of the machine, whereas the control device 90' at the left hand of the machine is adapted to operate with the laying of a yarn from the left to the right of the machine. For that purpose, and as will more clearly appear from Figures 8 to 11 inclusive, the cam 122 on the slur bar 22 is made in two parts 122a and 122b respectively having camming faces 123a and 123b facing each other but relatively spaced from one another. The relative adjustment and spacing of the cam parts 122a and 122b are such that when the slur bar 22 is at the extreme right of its reciprocating movement, the lever end portion 120 provided, in the manner hereinbefore stated, for the operation of the right hand control device 90, becomes located between the camming faces 123a and 123b, thus setting the pawl and ratchet mechanism 102 ready for operation, while the lever end portion 120', intended for the operation of the left hand control device 90', is in engagement with the camming face 123b (Figure 8).

With the subsequent movement of the slur bar 22 to the left, that is, in the direction of arrow

W (Figure 9) the cam part 122a is brought in contact with said lever end portion 120 causing the same to ride upon the camming face 123a, as illustrated in said Figure 9, accordingly actuating the ratchet mechanism of the right hand control device 90 to move the carrier bar in engagement therewith thus bringing the yarn controlled thereby in position for its subsequent transverse movement. When the slur bar 22 reaches the extreme left of its reciprocating movement, the lever end portion 120' of the left hand control device rides on the camming face 123b of the cam part 122b and falls between the latter and the camming face 123a of the cam part 122a, as represented in Figure 10, thereby preparing the ratchet mechanism of the left hand control device 90' for its operation.

Upon the return stroke of the slur bar 22 to the right, that is, in the direction indicated by the arrow E (Figure 11), the cam part 122b is brought in contact with said lever end 120', causing the same to ride upon the camming face 123b, as shown in Figure 11, to actuate said pawl and ratchet mechanism of the left hand control device 90' to move the carrier bar in engagement therewith to bring the yarn controlled thereby in position for its subsequent transverse movement.

By reason of the alternating actuation of the control devices, it will be appreciated that the adequate overlapping of the yarns for the formation of a proper split suture devoid of extra long loops is assured since, during the traversing movement of a yarn carrier rod selected by the three-carrier tackle for the formation of one course, the yarn carrier rod left at one end of the machine is brought to the required position for its selection for the formation of the second following course prior to its actual traversing movement for the formation of such second following course.

In this connection, it will be noted, particularly in Figures 8 and 10, that when the slur bar 22 is at its extreme right or left position, a spacing, as indicated at 155, occurs between the respective cam parts 122a and 122b, and the associated lever ends 120 and 120'. Because of this spacing, it will be appreciated that, since as is well known in the art, the function of the reverse Coulier motion causes the friction rod 24 which drives the carrier rod being utilized for the formation of a course, to move in unison with the slur bar 22, the positioning of a carrier rod for the formation of the second following course does not take place until after the driven carrier rod has moved for a certain distance, which assures the operation of the devices in the manner above stated.

At this point, attention is called to the fact that whereas the attachment and its function have been described as applied to a "legger" machine, to form the split high heel portions 4, the same attachment may be mounted on a "footer" machine in the same manner and to perform the same functions as hereinbefore explained for the production of the split sole portion 5.

It is pointed out that after the machine has finished knitting a set of stocking blanks, the attachment is again turned out of operative position and the machine placed in readiness for subsequent knitting of another set of blanks. The attachment may be reset while in inoperative position for its subsequent operation by manually rotating the hand wheel 156 which, as more clearly shown in Figure 13, is rigid with the shank portion 100 of the screw threaded spindle 98, the rotation of said hand wheel 156 thus causing

the rotation of the spindle 98 to place the sleeve 94 and its stop block 140 in position for said subsequent operation. However, it is to be understood that the resetting of the attachment may be done automatically, by providing the pattern chain 84 with the required number of buttons disposed to act upon the bell crank lever 82 in the same manner as hereinbefore described to actuate the control devices 90 and 90' when in inoperative position during the function of the machine to knit the leg portion of the stocking blanks above the point P thereof, so that said control devices will be brought to their initial location and there stand ready to be turned to operative position by the time knitting of the stocking blanks has reached said point P.

In concluding, I wish it to be understood that whereas I have shown and specifically described herein the preferred construction of my improved attachment, the same may embody various structure modifications without departing from the gist of the invention. Therefore, any modifications coming within the scope of the subjoined claims are to be considered within the spirit of the invention.

What I claim is:

1. In combination with the reciprocating slur bar, pattern chain, and Coulier motion of a full-fashioned knitting machine provided with an attachment for selectively operating a plurality of its carrier rods in repeated sequence: a mechanism actuated through the reciprocation of said slur bar for arresting the selectively operated carrier rods at various points in the course of their traversing stroke, and controlled in its actuation by the slur bar through said pattern chain mechanism and Coulier motion.

2. In combination with the reciprocating slur bar, pattern chain, and Coulier motion of a full-fashioned knitting machine provided with an attachment for selectively operating a plurality of its carrier rods in repeated sequence: a carrier arresting mechanism; means carried by the slur bar to reciprocate therewith, and acting upon said mechanism to actuate the same for arresting the selectively operated carrier rods at various points in the course of their traversing stroke; and means connected to the pattern chain and Coulier motion and operated thereby for controlling the actuation of said mechanism by said slur bar carried means.

3. In combination with the reciprocating slur bar, pattern chain, and Coulier motion of a full-fashioned knitting machine provided with an attachment for selectively operating a plurality of its carrier rods in repeated sequence: devices arranged upon the knitting machine for arresting the selected carrier rods at the right hand side and at the left hand side of their traversing stroke; means associated with said devices for operating the same to arrest said carrier rods at various points in the course of their stroke; means carried by the slur bar to reciprocate therewith and acting on the first mentioned means to actuate the same for its operation of the devices; and means connected to the pattern chain and Coulier motion and operated thereby for controlling the actuation of said first mentioned means by said slur bar carried means.

4. In combination with the reciprocating slur bar, pattern chain, and Coulier motion of a full-fashioned knitting machine provided with an attachment for selectively operating a plurality of its carrier rods in repeated sequence: devices arranged upon the knitting machine for arresting

the selected carrier rods at the right hand side, and at the left hand side of their traversing stroke; a ratchet mechanism associated with each of said devices for operating the same to arrest said carrier rods at various points in the course of their stroke; camming means carried by the slur bar to reciprocate therewith and acting on the ratchet mechanisms to actuate the same in their operation of the devices; and means connected to the pattern chain and Coulier motion and operated thereby for controlling the actuation of said ratchet mechanism by said camming means.

5. In combination with the reciprocating slur bar, pattern chain, and Coulier motion of a full-fashioned knitting machine provided with an attachment for selectively operating a plurality of its carrier rods in repeated sequence: a split suture attachment comprising a carrier rod stop supporting member movable longitudinally of the machine to cause the arrest of the carrier rods at various points in the course of their traversing stroke; a rotatable element in screw threaded engagement with said member to impart its longitudinal movement; means between said element and the slur bar and adapted to be actuated by the reciprocation of the latter for operating said element; and a mechanism connected to the pattern chain and Coulier motion and operated thereby for controlling the actuation of said means.

6. In combination with the reciprocating slur bar, pattern chain, and Coulier motion of a full-fashioned knitting machine provided with an attachment for selectively operating a plurality of its carrier rods in repeated sequence: a split suture attachment comprising a carrier rod stop supporting member movable longitudinally of the machine to cause the arrest of the carrier rods at various points in the course of their traversing stroke; a rotatable element in screw threaded engagement with said member to impart its longitudinal movement; a ratchet mechanism associated with said element to rotate the latter; a cam carried by the slur bar and disposed for cooperation with said ratchet mechanism to actuate the same through the reciprocation of the slur bar; and a mechanism connected to the pattern chain and Coulier motion and operated thereby controlling the ratchet mechanism in its actuation by the slur bar carried cam.

7. In combination with the reciprocating slur bar, pattern chain, and Coulier motion of a full-fashioned knitting machine provided with an attachment for selectively operating a plurality of its carrier rods in repeated sequence: a split suture attachment comprising a carrier rod control device arranged upon the machine for arresting the selected carrier rods at the right hand side of their traversing stroke; a carrier rod control device arranged upon the machine for arresting the selected carrier rods at the left hand side of their traversing stroke; means associated with each of said devices for operating the same to arrest said carrier rods at various points in the course of their stroke; means carried by the slur bar to reciprocate therewith and alternatively acting on the means associated with each of said control devices for the alternate operation thereof; and means connected to the pattern chain and Coulier motion and operated thereby for controlling the actuation of the first mentioned means by said slur bar carried means.

8. In combination with the reciprocating slur bar, pattern chain, and Coulier motion of a full-fashioned knitting machine provided with an at-

tachment for selectively operating a plurality of its carrier rods in repeated sequence: a split suture attachment comprising a carrier rod control device arranged upon the machine for arresting the selected carrier rods at the right hand side of their traversing stroke; a carrier rod control device arranged upon the machine for arresting the selected carrier rods at the left hand side of their traversing stroke; a ratchet mechanism associated with each of said devices for operating the same to arrest said carrier rods at various points in the course of their stroke; camming means carried by the slur bar to reciprocate therewith and acting on said ratchet mechanisms to actuate the same alternatively for the alternate operation of said devices; and means connected to the pattern chain and Coulier motion and operated thereby for controlling the actuation of said ratchet mechanisms by said camming means.

9. In a full-fashioned knitting machine provided with traversing carrier rods and having an attachment for selectively operating a plurality of said rods in repeated sequence to form a series of courses: a split suture attachment comprising a carrier rod controlling device arranged upon the machine for arresting the carrier rods at the right hand side of their traversing stroke; a carrier rod control device arranged upon the machine for arresting the carrier rods at the left hand side of their traversing stroke; a mechanism associated with each of said devices for operating the same to arrest the carrier rods at various points in the course of their stroke; a reciprocating cam consisting of two parts, one of said parts being disposed to act on the operating mechanism of one of said devices with the reciprocation of the cam in one direction, and the other of said parts being disposed to act on the operating mechanism of the other of said devices with the reciprocation of the cam in the other direction, whereby during the traversing movement of a selected carrier rod for the formation of one course, the carrier rod left at one side of the machine to be selected for subsequent traversing movement for the formation of the second following course may be brought in position for its selection prior to its actual traversing movement for the formation of such second following course.

10. In a full-fashioned knitting machine provided with a reciprocating slur bar and traversing carrier rods and having an attachment for selectively operating a plurality of said rods in repeated sequence to form a series of courses: a split suture attachment comprising a carrier rod controlling device arranged upon the machine for arresting the carrier rods at the right hand side of their traversing stroke; a carrier rod control device arranged upon the machine for arresting the carrier rods at the left hand side of their traversing stroke; a mechanism associated with each of said devices for operating the same to arrest the carrier rods at various points in the course of their stroke; a cam carried by the slur bar to reciprocate therewith and consisting of two parts, one of said cam parts being disposed to act on the operating mechanism of the right hand side control device with the reciprocation of the slur bar from right to left, and the other of said cam parts being disposed to act on the operating mechanism of the left hand side control device with reciprocation of the slur bar from left to right, whereby during the traversing movement of a selected carrier rod for the formation of one course, the carrier rod left at one side of the

machine to be selected for subsequent traversing movement for the formation of the second following course may be brought in position for its selection prior to its actual traversing movement for the formation of such second following course.

11. In combination with the reciprocating slur bar, pattern chain, and Coulier motion of a full-fashioned knitting machine provided with an attachment for selectively operating a plurality of its carrier rods in repeated sequence: a split suture attachment comprising a carrier rod controlling device arranged upon the machine for arresting the selected carrier rods at the right hand side of their traversing stroke; a carrier rod control device arranged upon the machine for arresting the selected carrier rods at the left hand side of their traversing stroke; a mechanism associated with each of said devices for operating the same to arrest the carrier rods at various points in the course of their stroke; a cam carried by the slur bar to reciprocate therewith and consisting of two parts, one of said parts being disposed to act on the operating mechanism of one of said devices with the reciprocation of the slur bar in one direction, and the other of said parts being disposed to act on the operating mechanism of the other of said devices with the reciprocation of the slur bar in the other direction; and means connected to the pattern chain and Coulier motion and operated thereby for controlling the actuation of said mechanisms by the cam parts in their respective movements with the reciprocation of the slur bar.

12. In combination with the reciprocating slur bar, pattern chain, and Coulier motion of a full-fashioned knitting machine provided with an attachment for selectively operating a plurality of its carrier rods in repeated sequence: a split suture attachment comprising a carrier rod control device arranged upon the machine for arresting the selected carrier rods at the right hand side of their traversing stroke; a carrier rod control device arranged upon the machine for arresting the selected carrier rods at the left hand side of their traversing stroke; a ratchet mechanism associated with each of said devices for operating the same to arrest said carrier rods at various points in the course of their right and left hand side strokes; a cam carried by the slur bar to reciprocate therewith and consisting of two parts, one of said parts being disposed to act on the ratchet mechanism of one of said devices with the reciprocation of the slur bar in one direction, and the other of said parts being disposed to act on the ratchet mechanism of the other of said devices with the reciprocation of the slur bar in the other direction; and means connected to the pattern chain and Coulier motion and operated thereby for controlling the actuation of said ratchet mechanisms by the cam parts in their respective movements with the reciprocation of the slur bar.

13. In combination with the reciprocating slur bar, pattern chain, and Coulier motion of a full-fashioned knitting machine provided with an attachment for selectively operating a plurality of its carrier rods in repeated sequence: a carrier arresting mechanism; means carried by the slur bar to reciprocate therewith and acting on said mechanism to actuate the same for arresting the selectively operated carrier rods at various points in the course of their traversing stroke; a cam slidably supported on the machine and functioning to act on said carrier arresting

mechanism for controlling the actuation thereof by said means; and mechanism connected to the pattern chain and Coulier motion for sliding said cam to perform its functions.

14. In combination with the reciprocating slur bar, pattern chain, and Coulier motion of a full-fashioned knitting machine provided with an attachment for selectively operating a plurality of its carrier rods in repeated sequence: devices arranged upon the knitting machine for arresting the selected carrier rods at the right hand side and at the left hand side of their traversing stroke; a ratchet mechanism associated with each of said devices for operating the same to arrest said carrier rods at various points in the course of their stroke; camming means carried by the slur bar to reciprocate therewith and acting on the ratchet mechanisms to actuate the same alternatively for the alternate operation of said devices; a cam slidably supported on the machine and functioning to act on said ratchet mechanisms for controlling the actuation thereof by said camming means; and means connected to the pattern chain and Coulier motion for sliding said cam to perform its function.

15. In combination with the reciprocating slur bar, pattern chain, and Coulier motion of a full-fashioned knitting machine provided with an attachment for selectively operating a plurality of its carrier rods in repeated sequence: a carrier arresting mechanism adjustably mounted for placement in active and inactive position; means carried by the slur bar to reciprocate therewith, and acting upon said mechanism to actuate the same for arresting the selectively operated carrier rods at various points in the course of their traversing stroke; means connected to the pattern chain and Coulier motion and operated thereby for controlling the actuation of said mechanism by said slur bar carried means; and means associated with said mechanism to reset the same when in inactive position.

16. In combination with the reciprocating slur bar, pattern chain, and Coulier motion of a full-fashioned knitting machine provided with an attachment for selectively operating a plurality of its carrier rods in repeated sequence: a carrier arresting mechanism adjustably mounted for placement in active and inactive position; means carried by the slur bar to reciprocate therewith, and acting upon said mechanism to actuate the same for arresting the selectively operated carrier rods at various points in the course of their traversing stroke; means connected to the pattern chain and Coulier motion and operated thereby for controlling the actuation of said mechanism by said slur bar carried means; and means arranged upon the pattern chain and disposed for action on said mechanism when in inactive position to reset the same automatically.

17. In combination with the reciprocating slur bar, pattern chain, and Coulier motion of a full-fashioned knitting machine provided with an attachment for selectively operating a plurality of its carrier rods in repeated sequence: a split suture attachment comprising a carrier rod control device arranged upon the machine for arresting the selected carrier rods at the right hand side of their traversing stroke; a carrier rod control device arranged upon the machine for arresting the selected carrier rods at the left hand side of their traversing stroke; a ratchet mechanism associated with each of said devices for operating the same to arrest said carrier rods at various points in the course of their right and left

hand strokes; a cam carried by the slur bar to reciprocate therewith and consisting of two parts, one of said parts being disposed to act on the ratchet mechanism of one of said devices with the reciprocation of the slur bar in one direction, and the other of said parts being disposed to act on the ratchet mechanism of the other of said devices with the reciprocation of the slur bar in the other direction; means connected to the pattern chain and Coulier motion and operated thereby for controlling the actuation of said ratchet mechanisms by the cam parts in their respective movements with the reciprocation of the slur bar; and means associated with said mechanisms to reset the same.

18. In combination with the reciprocating slur bar, pattern chain, and Coulier motion of a full-fashioned knitting machine provided with an attachment for selectively operating a plurality of its carrier rods in repeated sequence: a split suture attachment comprising a carrier rod control device arranged upon the machine for placement from inactive to active position for arresting the selected carrier rods at the right hand side of their traversing stroke; a carrier rod control device arranged upon the machine for placement from inactive to active position for arresting the selected carrier rods at the left hand side of their traversing stroke; a ratchet mechanism associated with each of said devices for operating the same to arrest said carrier rods at various points in the course of their right and left hand strokes; a cam carried by the slur bar to reciprocate therewith and consisting of two parts, one of said parts being disposed to act on the ratchet mechanism of one of said devices with the reciprocation of the slur bar in one direction, and the other of said parts being disposed to act on the ratchet mechanism of the other of said devices with the reciprocation of the slur bar in the other direction; means connected to the pattern chain and Coulier motion and operated thereby for controlling the actuation of said ratchet mechanisms by the cam parts in their respective movements with the reciprocation of the slur bar; and means arranged upon the pattern chain and disposed for action on said mechanisms when in inactive position to reset the same automatically.

19. In combination with the traversing carrier rods, reciprocating slur bar, pattern chain, and rocker arm of the Coulier motion of a full-fashioned knitting machine: a carrier arresting mechanism; means carried by the slur bar to reciprocate therewith, and acting upon said mechanism to actuate the same for its carrier arresting function; and a control mechanism associated with the pattern chain to be governed thereby and connected to the rocker arm of the Coulier motion to be operated thereby for controlling the actuation of said carrier arresting mechanism by said slur bar carrying means.

20. In combination with the traversing carrier rods, reciprocating slur bar, pattern chain, and rocker arm of the Coulier motion of a full-fashioned knitting machine: a carrier arresting mechanism; means carried by the slur bar to reciprocate therewith, and acting upon said mechanism to actuate the same for its carrier arresting function; a control mechanism associated with the pattern chain to be governed thereby and connected to the rocker arm of the Coulier motion to be operated thereby for controlling the actuation of said carrier arresting mechanism by said slur bar carrying means, said control mechanism including a link and lever system associated with

the carrier arresting mechanism, a cam slidably movable to adjust said system and displaceable to vary its adjusting function, means establishing a connection between the rocker arm and said cam to slidably move the latter, means normally acting on said cam to displace the same, latch means engaging said cam to hold the same against the normal action of the last mentioned means, and means under control of the pattern chain for releasing said latch means.

21. In a full-fashioned knitting machine provided with traversing carrier rods and having an attachment for selectively operating said rods: a split suture attachment comprising a carrier rod control device arranged upon the machine for

arresting the carrier rods at the right hand side of their traversing strokes, a carrier rod control device arranged upon the machine for arresting the carrier rods at the left hand side of their traversing strokes; a mechanism associated with each of said devices for operating the same to arrest said carrier rods at various points in the course of their right and left hand side strokes; and means including a slur bar operable to actuate said operating mechanisms during the traversing movements of the selected carrier rods for bringing the carrier rods to be selected in position for their selection prior to the actual traversing movements thereof.

FREDERICK C. GOOD.
